WALLET OR SIMILAR ARTICLE

Lee A. Blumenthal, Jamaica, N.Y., assignor to Peerless Plastics, Inc., New York, N.Y., a corporation of New York

Filed Mar. 1, 1965, Ser. No. 84,031

Term of patent 14 years

(Cl. D87—3)

FIG. 1 is a front elevational view of a wallet showing my new design, in closed condition;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a view similar to FIG. 1 but showing the wallet in partially opened condition;

FIG. 8 is a view similar to FIG. 7 but showing the wallet in more fully opened condition;

FIG. 9 is a view similar to FIG. 7 but showing the wallet in fully opened condition;

FIG. 10 is a top plan view of the wallet as seen in FIG. 9; and

FIG. 11 is a right-side elevational view of the wallet as seen in FIG. 9 but also showing the rear flap extended.

I claim:

The ornamental design for a wallet or similar article, substantially as shown.
